UNITED STATES PATENT OFFICE

ALLINE M. LYNCH, OF BLOOMFIELD, NEW JERSEY

DESIGN FOR A BOOK END

Application filed March 10, 1931. Serial No. 39,013. Term of patent 7 years.

To all whom it may concern:

Be it known that I, ALLINE M. LYNCH, a citizen of the United States, residing at Bloomfield, in the county of Essex and State of New Jersey, having invented a new, original, and ornamental Design for Book End, of which the following is a specification, reference being had to the accompanying drawings, forming part thereof.

The figures are perspective views of a book end showing my new design viewed respectively from the front and side thereof.

I claim:

The ornamental design for a book end as shown.

Signed at New York, in the county of New York and State of New York, this 6th day of March, 1931.

ALLINE M. LYNCH.
